(57) **CLAIM**

The ornamental design for a fishers skirted minnow lure, as shown.

DESCRIPTION

A portion of the disclosure of the patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a front perspective view of a fishers skirted minnow lure showing our new ornamental design.

FIG. 2 is a rear perspective view thereof.

FIG. 3 is a top view thereof.

FIG. 4 is a left side view thereof.

FIG. 5 is a right side view thereof; and,

FIG. 6 is a bottom view thereof.
